UNITED STATES PATENT OFFICE.

GEORGE EGART, OF MOOLEYVILLE, KENTUCKY.

SPIRIT-LEVEL.

SPECIFICATION forming part of Letters Patent No. 250,061, dated November 29, 1881.

Application filed May 19, 1881. (No model.)

To all whom it may concern:

Be it known that I, GEORGE EGART, of Mooleyville, in the county of Breckinridge and State of Kentucky, have invented a new and 5 useful Improvement in Spirit-Levels, which improvement is fully set forth in the following specification and accompanying drawings, in which—

Figure 1 is a side elevation of the level, and 10 Fig. 2 is a top view of the same.

The object of my invention is to improve the ordinary spirit-level; and it consists in having a frame for the tube containing the spirits, so constructed that the tube can readily be removed, and so that the tube, when placed in its 15 position, can be revolved or turned face downward, so as to prevent liability of breakage by contact with surrounding objects.

In the accompanying drawings, A represents the wood-work of the level, having a recess, B, cut out at the top edge centrally. This recess is covered by the usual edge or facing plate, C. Depending downward from the plate C at one end of the recess B is a bracket, G, 25 and at the opposite end of the recess is a block, E, secured to the plate C by means of a set-screw, L, so that the block E may be raised or lowered a limited distance for purposes which will be hereinafter fully explained.

30 A vertical bar, D, extending downward from the block E to near the bottom of the recess, is bent to assume a horizontal direction, and extends along the bottom of the recess to the opposite end, where it terminates in a right-angled upward extension, F, which is secured to the bracket G.

The tube H, preferably made of metal, is provided at one end with a screw-threaded socket adapted to receive the screw I, which passes 40 through the vertical arm D. The opposite end

of the tube has a journal, H', socketed in the upright F. The tube is further provided at this end with a wheel, J, provided on two opposite sides with notches J'. A spring, L', secured at one of its ends to the horizontal part 45 of the arm D, extends under the wheel J, passing through a slot in the upright F, and is then bent upwardly at right angles, ending at a point near the top face of the plate C. A depression, M', in the plate C, and a suitable perforation exposing the end of the spring M, enables the user to press the spring downward and release the part L' from the notch K on the under side of the wheel J. A depression, J', is also formed around the wheel J, and a 50 transverse slot exposes the wheel so that it can be manipulated.

The ordinary glass spirit-level tube is placed 55 within the tube H. The upper face of the metal tube being exposed permits the user to read 60 the indications as with the common level.

The set-screw L is designed to regulate the tube if out of level. The screw I permits the tube H to be withdrawn and replaced when broken. When in use the tube rests in the 65 level with the face up, as shown; but when not in use the spring M is depressed and the tube turned face downward, so as to prevent injury to the glass.

Having described my invention, what I claim 70 as new is—

The combination of the face-plate C, having the adjustable block E, the arms D F, and spring L', with the removable and revolving tube H, having the set-screw I and wheel J, as 75 herein specified.

GEORGE EGART.
